UNITED STATES PATENT OFFICE.

LEONARD NORWOOD BLAND, OF NORTH SYDNEY, NEW SOUTH WALES, AUSTRALIA, AS
SIGNOR TO BLAND MAGNETIC VALVES LIMITED, OF SYDNEY, NEW SOUTH WALES,
AUSTRALIA, A CORPORATION OF NEW SOUTH WALES, AUSTRALIA.

ELECTROMECHANICAL VALVE-OPERATING MEANS FOR INTERNAL-COMBUSTION ENGINES.

Application filed September 12, 1925, Serial No. 56,008, and in Australia October 20, 1924.

This invention relates to reversible valve operating means for internal-combustion engines. It relates in particular to valve operating means in which the valve movements 5 are controlled electro-magnetically and it consists in the novel features in electro-magnetic valve operating means which are hereinafter described in detail.

In all cases the inlet valves are closed by 10 springs as in usual practice in internal combustion engine construction; and they are lifted against the closing pressure of the spring by electro-magnetic action. The exhaust valves are normally held open by 15 springs instead of (as is the usual practice) being closed by springs; these valves are closed by electro-magnetic action operating against the lift of the springs. The solenoids release these valves during the 20 explosion stroke. As soon as the pressure within a cylinder falls to the predetermined point it becomes ineffectual for holding the exhaust valve down on its seat, and the spring then operating lifts the exhaust 25 valve. Automatic very rapid opening of the exhaust valves is thus effected irrespectively of the release of the solenoid pull on the valve, the lift of the valve happening instantly the pressure within the cylinder falls 30 to the predetermined point at which it is desirable that evacuation should commence; this is an important feature of the invention apart from the advantage of obtaining a rapid fullway opening for the exhaust without wire drawing at the commencement of 35 exhaust as must happen in the case of any cam-lifted valve. The automatic opening of the exhaust valve obedient to the pressure variation in the cylinder makes it practicable to effect reversing of the engine by 40 rocking the brush carriers. The brushes are set 90° apart and the carriers are adjustable around the rotary distributor barrel to regulate the contact positions on which depend 45 the timing of the inlet valve opening and the timing of the exhaust valve closing. In the case of single cylinder engines one segment of the rotary distributor with its two associated brushes mounted on a rocking 50 carrier controls the inlet valve; the exhaust valve is controlled through one segment of the rotary distributor for ahead running and through another segment of the rotary dis-

tributor for reverse running. The brushes which respectively run on these segments 55 are carried on the same rocker frame as the brushes which control the inlet valve. By a rocking movement of the brush carriers the change over is accomplished instantly for reverse instead of ahead running, or vice 60 versa. In the case of multiple cylinder engines, two rocking brush carriers, each carrying two rocking brushes, are cross coupled for every four cylinders, but the exhaust 65 valve control segments respectively operate with the solenoids of two cylinders only; this will be explained in detail with reference to Figs. 15 and 17.

In the case of multiple cylinder engines, 70 switches are provided in the solenoid circuits. By opening these switches the solenoids which they connect to the rotary distributor are rendered inoperative. In those circumstances the inlet valve of the cylinder which is cut out by opening the switches associated with its solenoids remains closed and the exhaust valve of that cylinder remains open. The engine can consequently be run on the remaining cylinders, leaving 75 the piston of the cut out cylinder to operate 80 idly and in safety. It is thus possible to use as many cylinders of a multiple cylinder engine as may be required, leaving the other cylinders of it inoperative.

The invention is usable with engines of 85 the Diesel type, an appropriate number of segments on the rotary distributor being used and circuited through a change-over switch to solenoids associated respectively with the free air valve, the fuel valve, the 90 starting valve, and the exhaust valve. As in the case of other internal combustion engines, the exhaust valve is normally opened by a spring, but is held closed against the spring by a solenoid whilst the solenoid is 95 energized. The other three valves of the engine are spring closed and are opened by the solenoids associated with them respectively when those solenoids are energized.

The solenoids are designed to exhibit only 100 a small degree of magnetic reluctance and their frame portions and are accordingly constructed of bronze, or other paramagnetic metal. An iron core piece which may be utilized as a slide bearing for the valve stem 105 is fitted in one end of the core, and the arma-

ture is fitted on the valve stem to work in the other end of the core, and this armature is formed with a flange head which is located at the end of the coil; this arrangement has 5 been found successful in practice for securing rapid and efficient operation of the solenoid and consequent satisfactory operation of the valve associated with it.

In the accompanying drawings:—

10 Fig. 1 is a transverse vertical section through a single cylinder four cycle internal combustion engine having solenoids controlling the valves, and a rotary distributor controlling the supply of current to the solenoids which are mounted on the side of the 15 crank case, the distributor being geared to the crank shaft in 2:1 ratio;

Fig. 2 is an enlarged sectional elevational view of the solenoid which controls the 20 inlet valve;

Fig. 3 is a similar view relating to the solenoid which controls the exhaust valve;

Fig. 4 is a perspective view of the rotary distributor;

25 Fig. 5 is a sectional elevation of the rotary distributor for a one cylinder engine, and Fig. 5^a shows the manual levers by which the distributor is adjusted for variation of valve timing and for effecting 30 reverse of the engine's direction of rotation;

Fig. 6 is an end view of the rotary distributor;

Figs. 7, 8, 9, and 10 are transverse sections through the rotary distributor on the 35 planes marked 7—7, 8—8, 9—9, and 10—10 respectively in Fig. 5;

40 Fig. 11 is a semi-diagrammatic view showing the engine piston at top stroke about to commence the down suction stroke, with the inlet valve just opened and the exhaust valve just closed;

Fig. 12 is a semi-diagrammatic view showing the piston at the bottom end of the suction stroke and both valves closed;

45 Fig. 13 is a semi-diagrammatic view showing the piston at top stroke and both valves closed, this being the full compression and ignition position;

Fig. 14 is a semi-diagrammatic view 50 showing the piston at the bottom end of the power stroke, the exhaust valve open and the inlet valve closed.

The rocking brushes and the rotary distributor segments are shown in these four 55 views, Figs. 11, 12, 13, and 14, circuited to the respective electro-magnets for ahead running, the rotary distributor segments being in each case shown in the position they would occupy for the piston and valve 60 positions which are respectively indicated in the several views.

Fig. 15 is a semi-diagrammatic view 65 showing portion of the cylinder head and the valve casing of a four cylinder engine with all the valves closed except the inlet

valve of No. 1 cylinder and the exhaust valve of No. 3 cylinder, and the several solenoids circuited through coupled switches to the brushes of the rotary distributor through which these solenoids are respectively controlled;

70 Fig. 16 is a longitudinal section through the rotary distributor for a four-cylinder engine;

Fig. 17 is an end elevation of the four 75 cylinder rotary distributor, showing the cross coupling arrangement used for ensuring corresponding rocking movement of the brush carrier spindles to change the running from "ahead" to "reverse"; and

80 Fig. 18 is a semi-diagrammatic view explanatory of the application of the invention to an engine of the "Diesel" type.

The direction of rotation of the rotary distributor for ahead running is shown by 85 the arrows in Figs. 7 to 14. The insulated segments on the rotary distributor are shown in full black areas, whilst the conductive segments are shown in unsectioned areas. For reverse running the distributor 90 rotates oppositely to the direction shown by the arrows.

In Fig. 1, 20 is the inlet valve, which, as 95 shown, is a valve of the well-known poppet type. The exhaust valve 21 is also a poppet valve. 22 is the inlet valve spring; it holds the valve 20 normally closed. 23 is the exhaust valve spring; its bottom end abuts on the fixed support 24 and its top end bears against the detachable collar 25 which is 100 keyed to the valve stem; this spring 25 operates normally to lift the exhaust valve 21 and hold it open. 26 is an inlet valve solenoid, and 27 an exhaust valve solenoid. 28 is the rotary distributor, and 29 the timing 105 adjustment control link which is pivotally attached to the rocker arm 30 which will be referred to later. 31 is the reversing control link which is pivotally connected to the rocker arm 32. The operation of this arm 110 will be referred to later. 33 is the engine piston.

In Fig. 2, 34 is the inlet valve stem, 35 the solenoid side frame, and 36 the bottom frame of the solenoid. The side frames 35 115 are constructed of brass or other paramagnetic metal, whilst the bottom frame 36 is of soft iron. It is mounted by brass pins or bolts 37 on an appropriate part of the engine framing, 38 being a brass plate or other magnetic insulator interposed between the frame 36 and the engine body. The top plate 39 of the frame is of soft iron and is tubularly extended as shown at 40 in to the core space of the solenoid coil 41. It extends about 120 half way into this core space and it provides a slide bearing for the inlet valve spindle 34. At the bottom end of it this valve spindle is 125 armed with a soft iron armature 42; this armature is flanged at 43 below the bottom 130

plate 36 in order to take advantage of the magnetic flux at the bottom end of the coil. When the coil is energized, the armature 42 and its flange extension 43 are pulled up 5 rapidly, compressing the spring 22 and opening the inlet valve 20.

A similar type of construction is used in the exhaust valve solenoid. As shown in Fig. 3, the exhaust valve spring 23 takes its 10 abutment on the brass cap 44 which is conveniently fitted on the top end of the solenoid frame. The magnetic core piece 45 is in this case located in the lower end of the core space of the coil 46, and the armature 47 has 15 its flange head portion 48 formed at the upper part of it where it will be under the influence of the top end of the coil 46. The armature is fixed to the valve spindle by means of a split pin or by any other mechanical 20 fastening.

50 is a link belt or other driving means for communicating half time rotational movement from the engine shaft to the rotary distributor shaft 51. 52 is an insulating body having a metal drum 53 of bronze fixed 25 upon it; the surface of this drum is interrupted by inserted segments 54 of vulcanite or like insulating material. For a single cylinder engine the disposition of the insulating segments 54 is shown in Figs. 11 to 14, the insulated portions being shown in full black in all the figures. 55 is a rocking frame sleeved over the shaft 51 and extended 30 through the outboard bearing 56. Upon it 35 the control arm 30 is fixed. This frame 55 carries the rock spindle 57 on which the brush holders are fixed by means of pinching screws 58 or otherwise. The overhanging end of the rock spindle 57 carries the saddle 40 piece 65. The links 29 and 31 and the levers 30 and 32 respectively are connected to the hand levers 59 and 60 which are mounted within easy reach of the driver of a vehicle in which the engine is installed to enable 45 him to control the valve timing and the direction of rotation of the engine. The lever 32 is carried on an arbor 62 which is offset from the side of the rocker frame 55. It is formed with claw ends 63-64; these 50 claw ends bear on a saddle piece 65 which is fixed on the rock spindle 57. When the lever 32 is pulled in one direction it bears the claw 63 down on the saddle piece 65, so rocking the spindle 57 and tipping the brush carriers 66 in one 55 direction. When the lever 32 is moved reversely its other claw 64 bears down on the saddle piece 65 and tips the brushes in the opposite direction. Thus either the ahead 60 brushes or the astern brushes are brought into contact with the metal surface of the distributor barrel 53 and the insulating segments 54 thereon, as the case may be.

As shown in Figs. 11 to 14, the first rock- 65 ing brush 67 supplies current to the dis-

tributor drum 53. It is immaterial whether this brush be rocked or not, but it is more convenient to fix it as a rocking brush as by bringing it to a middle position, that is by bringing the hand lever 60 to the notch 69, 70 both brushes are lifted and current is not supplied to the distributor from the battery 70. It is understood that current may be supplied either by a battery 70 or from a dynamo driven by the engine, or in the case 75 of a fixed engine, from any independent source. The left hand set of brushes, these brushes being each numbered 71, are the ahead running brushes. The brushes marked 72 in these figures are the reverse 80 running brushes. When the rock spindle 57 is moved in one direction the brushes 71 are brought to the contacting position and the brushes 72 are lifted, whilst in the other position of the spindle 57 the brushes 71 are 85 lifted and the brushes 72 brought to the contacting position. The particular method of mounting the brushes in the brush carrier is of no importance. A simple method of mounting which is quite effective is illustrated in Figs. 9 and 10. In these figures the brush carriers 66 are each armed on the back of them with springs 74. These springs bear on the back ends of carbon brushes 71-72 which are slidably housed in 90 holes drilled in a radial direction through the arm 66. 76 is a protective casing enclosing the brush assembly. This casing is fixed to the rocking frame 55. A similar arrangement is shown in Figs. 7 and 8. 100

A condenser 77 (Figs. 11-14) may be introduced in parallel in the circuit of each of the solenoids to minimize sparking troubles at the brush contacts on the distributor drum. 105

In the operation of a single cylinder engine, assuming that the brushes are set for ahead running, the inlet valve is opened by the operation of its solenoid when the brush 71 contacts with the conductive portion of 110 the distributor drum 53. This point is variable according to the adjustment of the hand lever 59 by which the frame 55 is rocked to traverse the brush assembly round the distributor drum sufficiently for timing 115 regulation. The actual time of opening of the inlet valve may accordingly be simultaneous with the top stroke position of the piston or may more or less precede or follow that position. In the suction stroke the inlet valve remains open and a charge is taken in. At the bottom end stroke, or very soon after the up-compression stroke is commenced, the inlet valve is closed. Meantime 120 the exhaust valve has been held closed by its solenoid. Both valves, being now closed, remain so, the inlet valve held by its spring and the exhaust valve held by its solenoid. At top stroke or thereabouts the charge is 125 fired and a condition of high pressure then 130

exists in the cylinder. The power stroke now commencing, the internal pressure progressively diminishes until a point is reached at which this pressure acting on the top of the exhaust valve is insufficient to hold it down against the lifting force of its spring 23. The exhaust valve solenoid is de-energized when the brush 71 serving it has passed on to the insulated segment of the distributor drum. That occurs soon after ignition has taken place and whilst a condition of high pressure exists within the cylinder. The exhaust valve, being thus held down by the pressure alone, is opened suddenly by the spring as soon as the internal pressure in the cylinder is insufficient to overcome the spring reaction. A very rapid opening of the exhaust valve thus occurs, and the burnt gas is evacuated in the usual way. The exhaust valve solenoid is energized again just about the time the piston is at top exhaust stroke, depending upon the adjustment of the timing lever. The same cycle of operations is continued indefinitely. When the brush carrier spindle 57 is rocked to bring the reversing brushes 72 into operation, the time at which the inlet and exhaust valves are respectively moved by the solenoids and released by them are appropriately changed to procure reverse running condition. An instant change may thus be effected from ahead to reverse, passing through the intermediate momentary position when both brushes are simultaneously lifted from the distributor drum.

In the case of a multiple cylinder engine, as for instance, an engine such as indicated in Fig. 15, the distributor drum may be arranged appropriately for any desired firing order of the respective cylinders. As shown in that figure, the arrangement is for the firing order 1-3-4-2. The inlet and exhaust valves are marked respectively I and E. The solenoids of each pair of them are circuited through coupled switches 80 to the related distributor brushes. When any switch 80 is opened the solenoids which it controls remain entirely inoperative, with the result that the inlet valve is held permanently closed by the action of its spring, whilst the exhaust valve is held permanently open by the action of its spring. That particular cylinder will therefore remain idle, its piston movement operating only to cause a to and fro flow of exhaust gas through the exhaust valve port whilst the other cylinders remain in effective operation.

A convenient arrangement is adopted in this case to minimize the number of segments in the distributor. Two brush carriers for the solenoids of cylinders which are 180° apart are fitted at diametrically opposite points in the rocking frame. Each distributor segment is thus made to serve two cylinders. But it is necessary to provide an

additional segment for reverse running for each pair of cylinders. The distributor drum will in this case have one continuous reception segment 80 (Fig. 15), two inlet valve control segments 81 and 82, and four exhaust valve segments 83, 84, 85 and 86. Two double brush carriers are provided for each of the inlet segments 81, 82, and two single brush carriers are provided for each of the exhaust segments 83 to 86. The cyclic operation of the several valves can be readily followed from the diagram.

In the distributor used in this case, it is necessary to provide an arrangement for reversing the brush carriers in pairs. In the arrangement already described with reference to Fig. 5, the reversal was effected by rocking the spindle 57, but in this case there are two spindles 90 and 91 each functionally corresponding with the rock spindle 57 (Fig. 5). A rocker claw 92 corresponding with the rocker claws 63-64 (Fig. 6) is provided to control the second set of brushes. This is mounted on an arbor 93 and is provided with an offset arm 94. This offset arm 94 is connected by a link 95 to a corresponding oppositely offset arm 96 on the upper claw piece which is numbered 63-64 in correspondence with the numeration on Fig. 6. 95

The operation of the system in connection with an engine of the Diesel type is shown in Fig. 18. In this case 100 is the free air valve, 101 the fuel valve, 102 the air pressure starting valve, and 104 the exhaust valve. The exhaust valve spring 105 is arranged to hold the exhaust valve 104 normally open. That valve is closed against the pressure of the spring 105 by the operation of its solenoid 106, the construction of which, like that of the other solenoids 107-108 and 109 is in this arrangement similar to that described already with reference to Figs. 2 and 3. The circuits through these solenoids are brought through a contact changing device 110. In the full line position of the movable element 111 of this device a circuit is established to the several brushes to procure the operation of the valves in cyclic order for normal running. 110 When the movable element 111 is pulled over to the dotted line position, a circuit is established governing only the starting air valve 102 and the exhaust valve 104. The engine may thus be turned over in the usual way, 115 and at the proper moment the movable element 111 reversed to the full line position, whereupon the air starting valve 102 will be rendered inoperative and the other three valves will be controlled in the usual cycle. 120 As in the preceding cases, the insulated segments on the distributor drum are shown in full black and the conductive segments are shown clear.

In the specification and in the claims the 130

term "solenoids" is to be construed as including electromagnets.

What I claim as my invention and desire to secure by Letters Patent is:—

- 5 1. Valve operating means for an internal combustion engine, comprising inlet valves having springs arranged to close them and solenoids arranged to open them against said springs; exhaust valves with springs arranged to open them and solenoids arranged to close them against said springs during the period in which the gas pressure acting on the valve heads is insufficient to overbalance the action of the opening springs and to hold them closed against said springs; and a distributor with a driving connection to the engine and arranged to close the circuit of a source of current through the respective solenoid windings in operative timed order.
- 10 2. Valve operating means according to claim 1 adapted for multi-cylinder engines, including a rotary barrel distributor having a rotatably adjustable brush carrier frame, two groups of brush carriers at diametrically opposite positions in said frame, means for rocking said frame to alter the timing

of the circuit make and break, and contact brushes on said carriers respectively wired to the valve operating solenoids.

30

3. Valve operating means including electro-magnets and a rotary segmental current distributor having two groups of brush carriers on a rocking frame as herein described, characterized in that the brush holders are double ended and are adapted to be tilted manually for adjustment to "ahead" and "reverse" running positions respectively, and in that the carriers are cross connected.

4. Valve operating means according to claim 3 including a switch in each electro-magnet circuit, said switches adapted for closing and opening said circuits, and characterized in that by the opening of the circuits relating to the solenoids associated with any particular cylinder the inlet valve of that cylinder is caused to remain closed and its exhaust valve to remain open whilst the other cylinders are functioning normally.

45

In testimony whereof I have signed my name to this specification.

50
